Inventor.

William W. Stickney

UNITED STATES PATENT OFFICE.

WILLIAM W. STICKNEY, OF ST. LOUIS, MISSOURI.

DRAIN-PIPE TURNER.

SPECIFICATION forming part of Letters Patent No. 269,549, dated December 26, 1882.

Application filed April 18, 1882. (No model.)

To all whom it may concern:

Be it known that I, WILLIAM WIER STICKNEY, a citizen of the United States, residing at St. Louis, in the State of Missouri, have invented a new and useful machine for turning over heavy socket drain-pipes while in the plastic condition, of which the following is a specification.

My invention relates to improvements for handling heavy socket drain-pipes made of clay or other plastic material. In making such pipes the socket end is usually formed first, so that the pipe when completed stands on its socket end, supported by what is called the "socket-plug;" but the pipe must be turned socket end up before setting it away to dry, because the weight of the pipe, which is often as much as four hundred pounds, would otherwise crush the socket if unsupported by the socket-plug; and the object of my invention is to enable any common workman of ordinary intelligence to turn over, end for end, any socket drain-pipe while in the plastic condition easily, quickly, and without injury to the pipe. I attain this object by the mechanism illustrated by the accompanying drawings, in which—

Figure 1 is a vertical section through the center of the entire machine, the wooden frame in which it works, and the socket-pipe standing in it, ready to be turned over. Fig. 2 is a top view of the machine and socket-plug, the pipe being left off. Fig. 3 is a front view of the cradle for preserving the cylindrical form of the pipe while turning. This cradle is semi-cylindrical in form, and made to fit the side of the pipe, each size of pipe requiring a different degree of concavity in the cradle. Fig. 4 is a top view of the cradle standing on end. Fig. 5 is a side view of the cradle standing on end. Fig. 6 is a top view of the upper part of the machine with the pipe standing in it and the end board clamped on, ready to be turned over. Fig. 7 is a front view of the clamping-bars and screws.

Similar letters refer to similar parts throughout the several views.

A B C D is the wooden frame, which constitutes the foundation of the machine, and to which the stationary parts of it are made fast, and this frame should be set up under the floor

of the room in which the pipes are to be made, directly under the pipe-press, and at such an elevation that the top A D of the frame shall be even with the floor.

A B B A' is a frame hung on axes C C', on which it revolves freely when not held stationary by the spring-latch D'.

E F F E' is a movable frame, sliding up and down, as required, through the guide-holes at H and H', and carrying the frame A B B A' by the axes C C'.

I I is the windlass, by which, in connection with the rope J J J, the pulleys K K, and the counterpoise L, the frame E F F E' is moved, carrying the frame A B B A', with its contents, up or down, as required.

M and M' are guide-rods to steady the movement of the frame E F F E' and keep it plumb.

N is the ratchet, and O the dog, which, in connection with the windlass I I, the rope J J J, the pulleys K K, the counterpoise L, and the frame E F F E', holds the frame A B B A', with its contents, at any required elevation.

A socket-plug, P P, corresponding in form to the inside of the socket of the pipe required to be made, is attached by the screw Q to the center of the cross-bar B B of the frame A B B A'; and R R is the pipe resting on the socket-plug P P as it stands when completed.

S S is the end board, to be clamped firmly to the small end of the pipe to prevent any longitudinal displacement while turning, and the cradle, Fig. 3, is to be clamped firmly to one side of the pipe to prevent any lateral displacement and preserve the cylindrical form of the pipe while turning.

The usual method of making socket drain-pipes of plastic clay is to press the clay through an annular opening in the bottom of a cylinder filled with clay, directly under which the socket-plug is placed inside a socket-die, which forms the socket as the clay is pressed down into it.

In Fig. 1 the pipe R R is represented as standing on the socket-plug P P with the end board, S S, and the cradle, Fig. 3, firmly clamped to the pipe by means of the clamping-bars U U' and the screws V V' V'' and the brace-pins W and W', all in readiness for turning the socket end up; but in order to illustrate

- more clearly the adjustments and action of this machine, suppose the pipe, with the cradle, the end board, and the clamping-bars and screws all removed, leaving the revolving frame empty of everything except the socket-plug. After fastening the frame A B B A' in an upright position by means of the spring-latch D, provided for that purpose, elevate the frame A B B A' by turning the windlass I I till the socket-plug P P enters the socket-die bolted to the overhanging clay-cylinder, and hold it there till the socket is formed. Then reverse the windlass and lower gradually as the pipe issues from the annular opening in the bottom of the clay-cylinder until a pipe of the required length is produced. Then cut the pipe off with a knife made for that purpose, and continue to lower the pipe till it will swing clear of the die above in turning, and interlock the dog O and the ratchet N. Then apply the cradle, Fig. 3, to that side of the pipe which will be the bottom while turning, by inserting the diagonal cleats Y Y' on the ends T T' of the cradle into the corresponding grooves, Z Z', in the legs B B of the frame A B B A', and slipping the cradle down in this diagonal direction till it fits accurately the side of the pipe. Then place the end board, S S, on the top end of the pipe, and place the clamping-bars in the slots in the ends of the legs B B of the frame A B B A', and put in above them the brace-pins W W', and clamp the end board, S S, by turning the screw V so as to separate the clamping-bars, thus pressing the upper one, U, against the brace-pins W W' and the lower one, U', against the cleats on the end board, S S; also clamp the cradle by turning down the screws V' V'' till they touch the upper ends of the side pieces, T T', of the cradle, and prevent it from moving longitudinally, while the diagonal cleats Y Y' and the diagonal grooves Z Z' prevent the cradle from moving in any other direction. The pipe is now ready to turn over, end for end, and one man can do the work by pulling out the spring-latch D, and rotating the hand-wheel X half round, thus accomplishing easily and quickly what requires the services of several men by the old methods of turning socket-pipes. After the pipe is turned socket end up disengage the dog O from the ratchet N, and lower the pipe to the floor, in which there should be an opening sufficient to admit the clamping-bars and screws, so that the cleats of the end board, S S, may rest firmly on the floor. Then pull out the pins W and W', which will allow the clamping-bars to fall on the hangers E and E' and the cradle to slide out of the diagonal grooves Z Z'. Then elevate the frame A B B A', carrying up the socket-plug out of the socket, thus leaving the pipe standing free and clear on the floor, ready for the truckman to take it away to dry.
- The combination of the windlass I I with the rope J J J, the pulleys K K, and the counterpoise L is substantially the same as what has commonly been in use for similar purposes long prior to my invention, and I do not therefore base any claim on such combination considered by itself.
- What I do claim as my invention, and desire to secure by Letters Patent, is—
1. The frame E F F E', in combination with the windlass I I, the rope J J J, the pulleys K K, and the counterpoise L to support and raise, and lower the socket-plug P P, substantially as herein set forth.
  2. The frame A B B A', in combination with the socket-plug P P, the axes C C', the hand-wheel X, the spring-latch D, the clamping-bars U and U', the screws V V' V'', the brace-pins W W', and the frame E F F E' to facilitate turning the pipe R R on the axes C C', substantially as herein set forth.

WILLIAM WIER STICKNEY.
